(57) **CLAIM**

I claim the ornamental design for a display screen with graphical user interface, as shown and described.

DESCRIPTION

FIG. 1 is a front view showing a display screen with graphical user interface of the present invention showing a first image in the sequence;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof; and,

FIG. 9 is a ninth image thereof.

The appearance of the transitional image sequentially transitions between FIGS. 1-9. No ornamental aspects are associated with the process or period in which one image transitions to another image.

The broken lines show parts of the display screen with graphical user interface that represent unclaimed subject matter and form no part of the claimed design.
